Primary Examiner — Cynthia Ramirez*(74) Attorney, Agent, or Firm* — Eric B. Fugett; Mark A. Pitchford; Pitchford Fugett, PLLC(57) **CLAIM**

The ornamental design for a pallet, as shown and described.

DESCRIPTION

FIG. 1 is an elevated perspective view of a pallet showing Applicant's invention.

FIG. 2 is a depressed perspective view of the pallet of FIG. 1.

FIG. 3 is a top plan view of the pallet of FIG. 1.

FIG. 4 is front side elevational view of the pallet of FIG. 1, the back side being a mirror image thereof.

FIG. 5 is bottom plan view of the pallet of FIG. 1; and, FIG. 6 is a left side elevational view of the pallet of FIG. 1, the right side being a mirror image thereof.

The broken lines in the figures depict portions of the pallet that form no part of the claimed design.
